UNITED STATES PATENT OFFICE.

FRANCIS I. DU PONT, OF WILMINGTON, DELAWARE, ASSIGNOR TO E. I. DU PONT DE NEMOURS POWDER COMPANY, OF WILMINGTON, DELAWARE, A CORPORATION OF NEW JERSEY.

APPARATUS FOR THE MANUFACTURE OF BLACK POWDER AND OTHER EXPLOSIVES.

964,550.

Specification of Letters Patent. Patented July 19, 1910.

Application filed July 28, 1909. Serial No. 510,070.

To all whom it may concern:

Be it known that I, FRANCIS I. DU PONT, a citizen of the United States, residing at Wilmington, county of Newcastle, and State 5 of Delaware, have invented a new and useful Improvement in Apparatus for the Manufacture of Black Powder and other Explosives, of which the following is a full, clear, and exact description, reference being had 10 to the accompanying drawings, which form a part of this specification.

Primarily my improved apparatus is intended for the manufacture of what is known as black powder, which usually consists of 15 a mixture of nitrate of soda, charcoal and sulfur.

The object of my invention is to produce, by the aid of the apparatus which is illustrated in this application, and which is 20 claimed in this and other applications filed as hereinafter indicated, black powder continuously and more safely and rapidly than is the general practice at the present time.

My invention can be best described by 25 reference to the accompanying drawings, in which—

Figure 1 is a general view partially in section of an apparatus embodying my invention. Fig. 2 is a detail sectional view 30 of pump. Fig. 3 is a side elevation of same. Fig. 4 is a detail view partially in section of distributor. Fig. 5 is a top plan view partially in section of distributor with a portion of casing removed. Fig. 6 is a 35 detail sectional view of drier. Fig. 7 is a section on line 7—7, Fig. 6. Fig. 8 is a section on line 8—8 Fig. 1. Fig. 9 is a detail view of driving and stripping pulley. Fig. 10 is a detail section of belt on driving 40 or stripping pulley.

I will first describe the general layout or apparatus for producing the powder in grain form, and then specifically point out the particular apparatus thereof which 45 forms the subject matter of this application.

In the other applications hereinafter mentioned, I will specifically describe other portions of the apparatus or layout and claim the same.

50 *a* is the mixing vessel in which is placed a solution containing 73 parts of nitrate of soda, 16 parts of charcoal and 11 parts of sulfur, to which is added 100 parts of water. In this vessel is the agitator *b*, which

is rotated by the shaft *c* on the upper end 55 of which is the gear *d*, driven by the gear *f* on the shaft *g*, which shaft is rotated by mechanism not shown. This mixing vessel has an inclined bottom *h*, converging to the hopper mouth *i*. In this converging bottom, 60 and on the shaft *c*, is the agitator *j*. The bottom of the shaft *c* is provided with a spiral or threaded portion *k*. When the material is placed in this mixer, by the revolution of the shaft and the consequent action 65 of the agitator or mixer *b*, an intimate mixture of the ingredients before described is caused to take place. The agitator or beater *j* prevents any settling or clogging of the hopper bottom of the mixing vessel *a*, 70 the screw *k* breaking up any solid matter tending to clog at that point. This hopper is connected with a pump of novel construction. This pump consists of the tube *l*, the walls of which are quite thick and one end 75 of which tube is connected to the nozzle or hopper *i*, and the other end to the pipe *m*. This tube is made of rubber, or a composition of rubber and canvas. It is supported vertically.

80 *n* are frames carrying the sprocket wheels *o* and the guide rails *p*. These sprocket wheels *o* are interconnected to revolve at the same speed by means of the gearing *q*.

85 *r* are the sprocket chains, to which chains are connected the rollers *t* carrying the guide rollers *s*, which bear against the guide rails *p*. As may be seen, these rollers *t* bear against the opposite sides of the tube *l*, and, in the movement of the sprocket chain de- 90 flat and release said tube, causing the material which is then in a liquid condition to be rapidly drawn through said tube and forced into the tube *m*. It has been omitted to state that the bottom of the vessel *a* is 95 provided with the jacket *u* through which steam is passed in the usual manner. The pipe *m* terminates in a distributing valve from which branches *v* extend to the evap- 100 orators *w*. These evaporators are jacketed tubes, provided with internal conveyers and are constructed and operate in the manner described and claimed in application filed by me November 18th, 1908, Serial No. 463,248, the only difference between the construction here illustrated and that of said application being that the steam jackets in 105 that application terminate in a header com-

mon to all, from which the steam passes; while in the present case, these jackets have independent connections *z* with a steam outlet *y*. Corresponding to that application, *z* 5 is a steam inlet pipe for the jackets, and *1* is the valve for controlling admission of steam. *2* is the shaft for driving through the gears *3* and *4*, the conveyer shafts *5*, on which shafts are conveyers, not shown, for 10 carrying the material through the evaporators, all as described and illustrated in my aforesaid application.

The distributing valve hereinbefore spoken of, see Figs. 4 and 5, I will now describe. 15 This valve consists of the casing, in which is the inlet *6*, into which passes the pipe *m* from which casing pass the outlets *7* to the various evaporators *w*. In the casing is the valve *8*, having a passage *9*. This valve is mounted upon the shaft *2*, so as to rotate in the casing. It is rotated quite rapidly, and, in the rotation of the shaft, the passage *9* registers consecutively with the passages *7*, by which means a like amount of material 20 is fed to each evaporator. The tubes of the evaporators terminate in a stack or chute *10*, the top of which is open and through which open end passes the vapor produced in said drying action. The lower end of this stack 25 *10* is provided with the jacketed portion *11*, through which steam or other heating medium is passed in the ordinary manner. Above this jacket is the grooved flange *12* in the groove of which are the edges of a 30 metal belt *13*. This metal belt *13* is provided with small orifices *14*, and at its edges, with larger orifices *15*.

In the evaporator above described, the treatment is such that the material comes 40 from said apparatus in a semi-liquid condition, preferably of the consistency of thick soup. Initially, in passing down this stack, the material may pass through the orifices *14* until the space between the orifices and the jacketed portion is filled, after which the orifices will become filled with the material in this stage of its manufacture. The large orifices *15* being covered by the flange 45 portion cannot receive any of this material. 50 This metal belt is a continuous belt passing over the rollers *17* and *18*, of which *17* is the driving wheel and will hereinafter be more fully described. In the travel of the belt after passing beyond the bottom of the 55 stack *10*, it passes through the cooling chamber *19*. During this passage into and through this chamber *19*, the belt is directly contacted with, at the top and bottom, to prevent the material in the orifices *14* from dropping out. The chamber *19* is provided 60 with a jacket through which, in the ordinary manner, cooling liquid or other cooling medium is passed. By passing through this chamber *19*, the material is solidified sufficiently to remain in the orifices. The belt 65

then passes through the drying chamber *21*, provided with jacketed walls, through which steam is passed.

22 and *23* are passages extending around the chamber, the passages *23* leading to the 70 atmosphere.

24 are inlet pipes extending from the tube or passage *25*, leading from the blower.

As may be seen, in the passage of this belt through this chamber, the material is subjected to the heat of the steam jacketed walls. Further, when air is blown through the openings *24*, by means of the passages 75 *22* it will pass into contact with the under surface of the perforated metal belt and will pass through the large orifices *15* in said belt and then pass along the upper side of said belt, escaping by the passages *23*. Thus the material on the belt is not only heated and dried by means of the heat in the walls or 80 jacket, but also by the air which is blown through. Reliance for heating this air may be had upon heat of the jackets before described in the chamber *21*, or it may be heated previous to entering the chamber. 85

The driving wheel is provided with projections *30*, which enter the large orifices *15* in the belt, and are used to drive the belt. There are also around this belt and in line with the orifices *14*, projections *26* of a size 90 such as will enter the orifices *14*. As the belt passes over these projections, they will enter the orifices *14*, forcing the powder blocks or grains out of the orifices, as shown in Fig. 9 of the drawings. 95

In order to insure the removal of the powder grains, a scraper *27* is provided, which, as shown, in the revolution of the wheel *17*, with certainty frees the powder grains from the belt. The powder thus 100 formed is in grains, which may be glazed, polished and treated by the ordinary processes for marketing.

I claim herein only that part of the apparatus which relates to the reception of 110 the material upon the belt and its subsequent treatment. The remainder of my invention with respect to said apparatus forms the subject matter of separate applications filed by me July 18, 1909, and serially numbered 510,068 and 510,069. 115

Having now fully described my invention, what I claim and desire to protect by Letters Patent is:

1. In an apparatus for forming and 120 treating powder grains, in combination, a receiving chamber having a heated closed lower portion, through which a traveling orificed belt passes.

2. In an apparatus for forming and 125 treating powder grains, in combination, a receiving chamber having a closed lower portion through which a traveling orificed belt passes, said belt traveling above the bottom of said lower portion.

3. In an apparatus for forming and treating powder grains, in combination, a traveling belt having perforations to receive the materials to be formed, a receiving chamber through which said belt passes, said belt traveling above the bottom of said receiving chamber. 70
4. In an apparatus for forming and treating powder grains, in combination, a traveling belt having perforations to receive the materials to be formed, a heated receiving chamber through which the said belt passes. 75
5. In an apparatus for forming and treating powder grains, in combination, a traveling belt having on its outer portions perforations and intermediate perforations to receive the material to be treated, a receiving chamber through which said belt passes and means for covering the first named perforations in order that they may not receive any material. 80
6. In an apparatus for forming and treating powder grains, in combination, a traveling belt having on its outer portions perforations and intermediate perforations to receive the material to be treated, a heated receiving chamber through which said belt passes and means for covering the first named perforations in order that they may not receive any material. 85
7. In an apparatus for forming and treating powder grains, in combination, a traveling belt having perforations to receive the material to be treated, a receiving chamber through which said belt passes, and a cooling chamber through which said belt passes after leaving the receiving chamber. 90
8. In an apparatus for forming and treating powder grains, in combination, a traveling belt having perforations to receive the material to be treated, a receiving chamber through which said belt passes, and a cooling chamber through which said belt passes after leaving the receiving chamber, said belt being, throughout its material-containing perforations, directly supported in passing to and through said cooling chamber. 95
9. In an apparatus for forming and treating powder grains, in combination, a traveling belt having perforations to receive the material to be treated, a receiving chamber through which said belt passes, and a cooling chamber through which said belt passes after leaving the receiving chamber, said belt being, throughout its material-containing perforations, covered above and below in passing to and through said cooling chamber. 100
10. In an apparatus for forming and treating powder grains, in combination, a traveling belt having perforations to receive the material to be treated, a heated receiving chamber through which said belt passes, and a cooling chamber through which said belt passes after leaving the receiving chamber. 105
11. In an apparatus for forming and treating powder grains, in combination, a traveling belt having perforations to receive the material to be treated, a heated receiving chamber through which said belt passes, and a cooling chamber through which said belt passes after leaving the receiving chamber, said belt being, throughout its operative perforations, directly supported in passing to and through said cooling chamber. 110
12. In an apparatus for forming and treating powder grains, in combination, a traveling belt having perforations to receive the material to be treated, a heated receiving chamber through which said belt passes, and a cooling chamber through which said belt passes after leaving the receiving chamber, said belt being, throughout its operative perforations, covered above and below in passing to and through said cooling chamber. 115
13. In an apparatus for forming and treating powder grains, in combination, a traveling belt having throughout a portion of its width, perforations or notches, and throughout another portion of its width perforations to receive the material to be treated, a receiving chamber through which said belt passes, and means to cover the first named perforations while the belt passes through the receiving chamber, and a cooling chamber through which said belt passes after leaving the receiving chamber. 120
14. In an apparatus for forming and treating powder grains, in combination, a traveling belt having throughout a portion of its width, perforations or notches, and throughout another portion of its width perforations to receive the material to be treated, a receiving chamber through which said belt passes, and means to cover the first named perforations while the belt passes through the receiving chamber, and a cooling chamber through which said belt passes after leaving the receiving chamber, said belt throughout the extent of the last named perforations being covered both above and below in passing to and through said cooling chamber. 125
15. In an apparatus for forming and treating powder grains, in combination, a traveling belt having throughout a portion of its width, perforations, and throughout another portion of its width perforations to receive the material to be treated, a receiving chamber through which said belt passes, and means to cover the first named perforations while the belt passes through the receiving chamber, and a cooling chamber through which said belt passes after leaving the receiving chamber, said belt throughout the extent of the last named perforations being directly supported in passing to and through said cooling chamber. 130
16. In an apparatus for forming and treating powder grains, in combination, a drying

- chamber, a traveling belt in said drying chamber, said belt having perforations adapted to receive the material to be dried, said drying chamber having heated walls 5 there being passages through said heated walls, but not in communication with the interior of the heated walls, some of which are to admit heated air and others to allow the escape of the same, said belt having, in 10 addition to the perforations to receive the material, other perforations through which the air may pass.
17. In an apparatus for forming and treating powder grains, in combination, a traveling belt having perforations, means to fill certain of said perforations with the material, means to solidify said material in 15 said perforations, a drying chamber through which said belt passes, said chamber having sectional jacketed walls, there being passages between sections, a source of drying fluid, for example, heated air, in communication with the passages on one side of the belt and outlets in communication with the 20 passages on the opposite side of the belt.
18. In an apparatus for forming and treating powder grains, in combination, a traveling belt having perforations, means to fill certain of the said perforations with material, means of solidifying said material in 25 said perforations, a drying chamber through which said belt passes, said chamber having sectional jacketed walls, there being passages between sections, a source of heating fluid, for example, hot air, in communication 30 with the passages on one side of the belt, and outlets in communication with the passages on the opposite side of the belt, a pulley beyond said drying chamber over which said belt passes, projections on said pulley 35 in alinement with said perforations, and adapted in the passage of the belt to enter said perforations and force the material therefrom.
- 45 19. In an apparatus for forming and treating powder grains, in combination, a traveling belt having perforations, means to fill certain of said perforations with the material, means to solidify or partially solidify 50 said material in said perforations, a drying chamber through which said belt passes, said chamber having sectional jacketed walls, there being passages between sections, a source of heating fluid, for example, hot air, in communication 55 with passages on one side of the belt and outlets in communication with passages on the opposite side of the belt, and perforations in said belt not filled with the material through which the air or 60 other fluid can pass from the passages on the one side of the belt to the passages on the other side of the belt, a pulley beyond said drying chamber over which said belt passes, projections on said pulley 65 in alinement with said perforations, and adapted in the pas-

sage of the belt to enter said perforations and force the material therefrom, and a scraper, the active end of which is in alinement with the upper surface of said belt.

20. In an apparatus for forming and 70 treating powder grains, in combination, a drying chamber, a traveling belt in said drying chamber, said belt having perforations adapted to receive the material, a source of heating fluid, for example, hot air, 75 communication between said heating fluid and said chamber on one side of the belt, and an outlet on the opposite side of the belt, and perforations or passages to permit the heating fluid to pass from one side of 80 the belt to the other.

21. In an apparatus for forming and treating powder grains, in combination, a 85 drying chamber, a traveling belt in said drying chamber, said belt having perforations adapted to receive the material, a source of heating fluid, for example, hot air, and means to force said heating fluid to travel for a certain distance on both sides of said belt.

22. In an apparatus for forming and 90 treating powder grains, in combination, a traveling belt having perforations, means to fill certain of said perforations with material, means to solidify or partially solidify 95 said material in said perforations, a drying chamber through which said belt passes, a source of heating fluid, for example, hot air, communication between said source of heating fluid and said chamber, and means 100 to force said heating fluid to travel for a certain distance along both sides of said belt, till it has taken up a certain amount of moisture from the material and means to force fresh heating fluid, for example, 105 hot air along another portion of said belt on both sides and to escape, having taken up a further portion of moisture from the material and sufficient repetition of this arrangement to insure that the material will 110 be thoroughly dried.

23. In an apparatus for forming and 115 treating powder grains, a traveling belt having perforations, means to fill certain of said perforations with the material, means to solidify or partially solidify said material in said perforations, means to support said belt to prevent the material from falling out of the perforations before it is sufficiently solidified, a drying chamber 120 through which said belt passes, a source of heating fluid, for example, hot air, communication between said heating fluid and said chamber, and an outlet so arranged that the heating fluid will be forced into 125 contact with both sides of said belt, a pulley beyond said drying chamber over which said belt passes, projections on said pulley in alinement with said perforations and adapted in the passage of the said belt to 130

enter said perforations and force the material therefrom.

24. In an apparatus for forming and treating powder grains, a traveling belt having perforations, means to fill certain of said perforations with the material, means to solidify or partially solidify said material in said perforations, means to support said belt to prevent the material from falling out of the perforations before it is sufficiently solidified, a drying chamber through which said belt passes, a source of heating fluid, for example, hot air, communication between said heating fluid and said chamber, and an outlet so arranged that the heating fluid will be forced into contact with

both sides of said belt, a pulley beyond said drying chamber over which said belt passes, projections on said pulley in alinement with said perforations and adapted in the passage of the said belt to enter said perforations and force the material therefrom, and a scraper, the active end of which is in alinement with the upper surface of the said belt.

20
In testimony of which invention, I have hereunto set my hand, at Wilmington, Del., on this 28d day of July, 1909.
